FLOOR TOOL FOR AIR-METHOD CLEANING SYSTEMS

Daniel Benson Replogle, Berkeley, Calif., and Harold E. Queen, Washington, D. C., assignors, by direct and mesne assignments, to Citizens Trust Company, Toledo, Ohio, a corporation of Ohio, as trustee

Application May 23, 1932, Serial No. 613,068
In Great Britain June 17, 1931

7 Claims. (Cl. 15—156)

This invention pertains to floor tools such as are used in connection with the suction pipes of so-called vacuum cleaner systems, but is more particularly applicable to that form of electrical 5 motor driven portable cleaner in which suction producing means are directly connected to the suction pipe that carries the floor cleaning tool, and are moved about manually with the pipe, or some part of it, used as a handle. Such cleaners 10 are known commercially under the registered trade-mark "Air-Way".

The "Air-Way" type device, which by reason of the limited weight, may be moved conveniently about by hand, should have all its parts meticulously scaled down to very light and strong forms; and moreover provision for carrying the principal element of weight, its power plant, is properly to be found in a proper set of rollers, and a smooth working face of the tool which operates upon the 20 floor of fabric to be cleaned.

Furthermore the tool to be used for general service on such a device should have characteristics adapting it, or making it readily adaptable to at least four distinct functions of service:

25 First, it should be adaptable to removing fine and deeply imbedded dust from floor covering fabrics of all varieties. Second, it should be efficient for removing lint, hair, floss, ravelings and the like from the surface of, and from entanglement with, the pile or nap of carpets and rugs. Third, it should be so arranged as to dispose and direct the air currents which do the cleaning, so that heavy and gravelly grit found upon floors or within the fabric, may be rolled up 30 and into the suction pipe, instead of having to be lifted vertically, at the throat or junction of the suction pipe and the tool. And fourth, it should be constructed with a view to carrying away considerable quantities of sewing room litter, leaves from house plants, nut shells, cigarette and tobacco remnants, feathers and the like, without becoming choked or obstructed thereby. And withal it should be adapted to clean hard 35 surfaces or floors without scratching or injuring the paint, and without abrading or discoloring the fabrics to which it is applied.

Besides these functions, the parts of the tool most exposed to wear should be conveniently renewable by replacement so as to preserve the 40 complete efficacy of its service.

The present invention has been produced to attain the various objects enumerated, and such other objects as may be stated in the further description.

45 According to this invention, there is provided

a cleaning tool of the type indicated, wherein the lips outlining the mouth thereof are disposed between a pair of supporting end rollers, and substantially within the cylindrical limits delineated by, and along the extended common axes between said rollers. Provision is also made in a cleaning tool of the type indicated for attachment thereto, along a lip of the mouth thereof, of a supplemental lip, diverse in abrasive quality from the lips of the tool, and designed to be 5 brought into action by tilting said tool. The invention also consists of a cleaning tool of the type indicated, wherein the body portion thereof is adapted to have spring-actuated supporting rollers arranged to be manually attachable to and 10 detachable from said body, for diversification of the service of said tool.

With cleaners of this type lightness of the floor tool is a particularly important feature. Consequently one of the objects of the invention is to 20 construct the tool with its walls as thin as possible consistent with strength. Another important feature is the provision of a relatively narrow mouth for the tool, as compared with the diameter within the tool above the mouth. A further 25 object is to form a tool or nozzle within which eddy currents may be avoided so far as possible. A further object of the invention is to provide a tool which may be manufactured at the 30 lowest possible cost.

According to the present embodiment of the invention the tool is preferably composed of two substantially equal longitudinally divided halves, constituting an upper and a lower member, which are suitably joined together. This construction 35 makes it possible to stamp the tool out of sheet metal or to die cast it, and at the same time to provide the desired restricted mouth or inlet portion.

A further feature of the invention resides in the 40 fact that the upper and lower portions of the floor tool carry respectively upper and lower halves of an air outlet conduit. A further object of the invention is to provide an improved 45 form of end pocket for receiving the supporting shanks of the end rollers which carry the weight of the tool. A further object of the invention is to provide an improved means for detachably connecting the floor tool to a suction pipe or 50 handle.

Further objects of the invention will be apparent from the accompanying drawings and the following detailed description as amplified by 55 the appended claims.

In the drawings:

Fig. 1 is a perspective view of the complete cleaner;

Fig. 2 is a side view on an enlarged scale of the floor tool detached from the remainder of the cleaner;

Fig. 3 is a side view of the upper member of the floor tool before joining to the lower member;

Fig. 4 is a side view of the lower member of the floor tool, before joining to the upper member;

Fig. 5 is a top view of the member shown in Fig. 3;

Fig. 6 is a top view of the member shown in Fig. 4;

Fig. 7 is a rear view of the member shown in Fig. 4;

Fig. 8 is a rear view of the member shown in Fig. 3;

Fig. 9 is a rear view of the upper and lower members of the floor tool assembled, the tool being partly broken away to illustrate a supporting roller in the relaxed position, showing the cover mounted on the shank of the roller to cover the end of the tool body;

Fig. 10 is a bottom view of the lower member of the floor tool;

Fig. 11 is a fragmentary detail section on an enlarged scale through the spring latch whereby the floor tool is attached to the cleaner handle;

Fig. 12 is a rear view of the brush attachment;

Fig. 13 is a side view of the floor tool partly broken away and sectioned to show the method of attaching the brush;

Fig. 13a is a fragmentary perspective view showing one end of the nozzle with portions broken away and illustrating the mode of attachment of the end rollers;

Fig. 14 is a side view of the floor tool with the reversible brush attached felt side down, the rollers having been removed;

Fig. 15 shows a blank sheet of hard fibre used to form an end closing cover as carried on the roller shank;

Fig. 16 shows a step in the process of forming the cover;

Fig. 17 shows a detent to secure the cover to the roller shank;

Characters of reference used in any of the views denote like or similar parts where they are used in the other views.

Referring particularly to Figs. 2 to 10, a lower trough-shaped member 1, which may be formed by pressing from sheet metal, is joined by welding or other suitable means to a member 2 which as shown is roughly an inverted trough. Member 2 has a welt or coping 3 pressed on its edge designed to lap over the edge 4 of the member 1. This welt 3 overlaps edge 4 at all points except for a very short length 5 where members 1 and 2 together form a cylindrical conduit 6 from the tool. As shown in section in Fig. 2, a cylindrical ring 7, having a flanged end 8, is placed over this cylindrical conduit 6 serving to join the members 1 and 2 and cover the butt joint at 5.

Member 1 may be formed by pressing from a flat sheet to, roughly, a trough shape one side of which, at the center, takes a half cylindrical form 8a. A slit 9 is made in the bottom of member 1, and the material on either side of the slit 9 is rolled back to form beads 10-10 over which are slipped slotted tubes 11-11 of hard fibre, rubber, rawhide, or other non-metallic material, forming the lips of the mouth of the tool, which lips constitute stroker members. As shown in

Figs. 2 and 10, the fibre lips or strokers 11 may be cut to form tabs or teeth 49 over a part of their length near their mid section. These teeth may be formed by saw cuts transverse of the tubes 11 or sheared up by pressing. The two sets 5 of teeth point into the mouth of the floor tool and are normally parallel to the floor.

Member 2 is formed by pressing from a flat sheet approximately a trough shape one side of which, at the center, takes a half cylindrical 10 form 12. When inverted over member 1, member 2 constitutes a cover. Two pockets 13-13 are formed in member 2, to receive supporting roller shanks 14 by pressing and shearing inward a tab 15 which then forms part of the floor of the 15 pocket. The floor of the pocket is extended the length of the pockets 13-13, and forms an air-tight ceiling for the main chamber of the tool, by a channel shaped strip 16 welded to tab 15 and the sides of member 2. 20

The open end of pocket 13 has two turned-down tabs 17-17 adapted to engage two shoulders 18-18 (see Fig. 13a) on the spring 19, which is attached to shank 14 of supporting roller 20, thus retaining the shank in the pocket. 25

Two downwardly opening recesses 21-21 are formed between the welt 3 of member 2 and the edge 4 of member 1 to receive the hooks 22-22 of attachment brush 23, shown in Figs. 12, 13 and 14. 30

This floor tool formed by the assembling of members 1 and 2 is roughly a cylindrical shaped cross head 24 on conduit shank 6. The lips or strokers 11 are within the limits of an imaginary cylinder defined by the rollers 20-20. 35

Openings 25-25 remain at either end of the tool between ends of the beads 10-10. Covers 26-26 carried by roller shanks 15-15 slidably cover these openings 25 when springs 19-19 are in the relaxed position shown in Fig. 9 and said 40 openings become uncovered when the head is pressed down on the floor tensing springs 19-19.

Covers 26-26 are preferably pressed from flat sheets of hard fibre as illustrated in Fig. 15, and are curled by a hot iron to a U shape as illustrated in Fig. 16. Detent 27 illustrated in Figs. 17 and 9 retains cover 26 onto shank 14, the heel 28 of the cover bearing against the downturned part 29 of shank 15, thus exerting a pressure, due to the elasticity of the fibre, the toe 30 of the 50 cover pressing against the end of the tool at opening 25.

The assembled roller supports 14 and covers 26 are detachable together. The flat spring 19 is designed to be compressed by pressing with the 55 thumb on the top 20 which unhooks it, whereupon it may slip away, with the shank to which it is riveted, from the pocket 13.

It is to be observed that the tool is operative, with the rollers and covers removed from either 60 or both its ends. When thus removed a flat stream of air is directed along the surface being cleaned, coming in between the then exposed ends of the strokers, which may with great advantage be applied to corners along base boards, which 65 are not accessible with tools as commonly used. The same flat stream effect is had on the nap of carpets and rugs as well as upon linoleums and bare floors when the rollers are left in place and the operator presses down on the tool so that the 70 ends of the strokers are pressed beyond the range of the lower edges of the covers. The arrangement prevents the sealing against air current when the tool is pressed down where no current could pass through the floor covering fabric, but 75

permits sealing all around the mouth of the tool when the fabric is lifted by suction and the action of the springs 19—19 from the floor, and thus promotes the action of drawing the air current 5 through the fabric itself with the consequent dislodgement of dirt which may be imbedded in the fabric.

Referring particularly to Fig. 2, a short piece of thin walled metal tube is swaged to an elbow 10 31 of approximately 22½ degrees. To the shorter leg 32 of elbow 31 is welded a cylindrical shaped ring 33 having a flanged end 34 adapted to be swaged over the flange 8 of ring 7, thus assembling elbow 31 to members 1 and 2 with a rotatable joint 51.

Referring particularly to Figs. 1, 2 and 11, a slip joint between elbow 31 and tubular conduit handle 39 operably connects the floor tool to the handle. A spring latch 35 attached to elbow 31 20 carries a peg 36 adapted to extend through a hole 37 in elbow 31 which registers with a hole 38 in a tubular conduit 39. By raising the end 40 of spring latch 35 the peg 36 is withdrawn from the holes 37 and 38 and the floor tool is 25 detached from the tubular conduit handle 39.

Referring to Fig. 12, an attachment brush 23 composed of a strip of wood 41 carries bristles 42 and a strip of felt 43 retained back to back by two plates 44—44 and rivets or bolts 45. Two 30 spring clips 46—46 are carried under the heads of the rivets 45 and may be rotated around these rivets. These spring clips 46—46 each have at the shorter end a hook 22 adapted to engage recess 21 in the floor tool, and at the longer end a hook 47 adapted to hook over the rear top edge 48 of the floor tool, thus retaining the brush onto the tool.

It is to be observed that the device attaches similarly whether the felt edge or the brush edge 40 is disposed downwardly, according to the kind of service required, and in either case the attachment is held obliquely so as to poise the operating edge close to the mouth of the tool. This arrangement is novel and important because particles dislodged by it are to be delivered 45 up to the air stream to be carried away.

In the operation of the assembled device as a whole, the combined brush and felt attachment may be left in place, high enough above the surface being cleaned so that the mouth only of the tool is regularly in actual service, thus avoiding unnecessary brushing or scraping where there are no resistant particles to remove. But where, for example, ravelling of silk or other particle 50 persists, the operator by raising the handle of the cleaner tilts the tool on its longitudinal axis, which is in line with the spindle in each roller, and brings as much pressure to bear as may be needed at the spot and at the time required. Threads, after having been impaled on the bristles of the brush by backward strokes of the tool, are wiped off on the forward stroke, in close proximity or directly underneath the forward stroker at the mouth of the tool.

65 The swivel joint permits rotative adjustment of the tool with respect to the pipe handle, obliquely to the axis thereof.

The tool is so constructed that amplified space is all the way contiguous to the restricted mouth, and special amplification is provided for at and in front of the throat of the tool, so that choking up with litter will not occur; and the lower wall in the throat of the tool merges with the rear lip in such fashion that a gradual inclined plane is 70 provided whereby heavy particles like sand and

grit may be rolled up into the pipe handle by the air stream, when the stream may not be strong enough, by reason of restriction due to close contacting of the lips with the floor, to lift the heavier particles vertically upward.

5

The generally cylindrical outline of the body of the tool permits great strength when constructed with thin and light metallic walls which approach to, and form the mouth of the tool within the cylindrical delineation outlined by the 10 soft rubber rollers, centralized with the axis thereof, and attached as shown at the ends. And confining the mouth of the tool within such cylindrical limits provides the great advantage of permitting the swinging upward and downward 15 handle motion, consequent in sweeping, without breaking the effective contact line of the mouth.

Since it is well known that metals rubbed over light colored fabrics discolors and injures them, there has been resorted to the novel feature of 20 covering the metallic lips of the tool mouth with removable and replaceable coverings or strokers made of hard fibre, or other suitable material, thus providing against such injury.

The rounded lips formed by the tubular strokers 25 make for easy propulsion across the surface to be cleaned, and should these lips become flattened with wear, they are readily removable by sliding off end-wise so that replacement of the worn part may be had.

30

While in the specific embodiment of the invention as above described, reference has been made to the use of sheet metal as the material from which the tool is formed, other suitable materials may be employed, as for example various synthetic plastic compositions, such as "bakelite" or the like, particularly if reinforced by fibre or the like incorporated within the body of the composition, or fibrous compositions suitably impregnated may be shaped or molded into the desired form 40 without departing from the spirit of the invention. Where sheet steel is employed, walls having a thickness of approximately one-thirty-second of an inch are satisfactory, and owing to the rounded form of the tool which lends maximum 45 strength thereto, will not be marred or dented by contact with furniture or the like.

We claim:

1. A stroker element for the floor tool of a suction cleaner, comprising a slotted tube of non-metallic material, having thread-picking notches 50 formed therein.

2. A floor tool having a lip portion and stroker element comprising a slotted tube of non-metallic material covering said lip portion, said stroker 55 element having thread-picking members formed integral therewith.

3. A floor tool having a pair of co-planar lips, tubular stroker elements of non-metallic material covering said lips, and thread-picking elements 60 formed integral with the strokers, all said elements of both strokers lying in a single plane which in the normal position of the floor tool is parallel to the floor.

4. A floor tool for suction cleaners comprising an upper and a lower half, consisting of complementary sheet metal stampings, one fitting over the other with a fluid-tight overlapping fit, an outlet conduit comprising upper and lower complementary trough-like members formed integral with the upper and lower portions respectively of the floor tool, one trough member overlapping the other at the longitudinal edges thereof, and a ring connecting the end portions of said com- 70 75

plementary members and forming an air-tight joint.

5. A floor tool of generally cylindrical form formed from sheet material, and including a pair 5 of spaced parallel lips outlining a mouth having end openings, said lips having downwardly and outwardly rolled beads integral therewith formed from the material used to provide the mouth, said beaded lips providing end openings 10 for the tool.

6. An elongated sheet metal floor tool including an upper and end walls, and an end pocket for a roller support, said pocket including a floor portion spaced for at least a part of its length 15 from the upper wall of the floor tool, said floor portion including a tab cut from an end wall and

bent inwardly, leaving an end opening for the insertion of the roller support, and an extension member secured at one end to said tab and at its other end to the upper wall of the floor tool.

7. In a floor tool of the character described, 5 a pocket for a roller support opening inwardly from one end of the tool, and the upper wall of said tool having a pair of spaced integral tabs extending downwardly into said pocket, a roller having a shank for insertion into said pocket, 10 and a spring support carried by said shank and having a pair of shoulders adjacent the free end thereof for detachable engagement with said tabs.
